BOILER

Paul W. Vandenberg, Elmhurst, Ill., assignor to
Crane Co., Chicago, Ill., a corporation of Illinois

Application August 16, 1939, Serial No. 290,418

4 Claims. (Cl. 122—225)

This invention relates to steam and hot water boilers and more particularly it relates either to coal, gas or oil fired boilers characterized by upright or vertically extending sections. The novel construction of the boiler sections has been evolved to create greater efficiency in the boiler operation and to make available easily and economically new advantages and conveniences in the manufacture and assembly of the equipment.

It is well known by those skilled in the art that in a coal or solid fuel burning boiler, whether the stoking is done by hand or by automatic means, the arrangement of the flue passages should preferably conform to the general construction of an up-draft type of boiler. It is also well known that in a gas or oil fired boiler, in order to procure the greatest efficiency in the operation of the boiler, the arrangement of the flue passages should conform to the general construction of a down-draft type boiler. However, boilers presently available are not adaptable to such convenient or ready conversion from solid fuel burning respectively to gas or liquid fuel burning, or vice versa, without an appreciable reduction in the operating efficiencies of the boilers.

Accordingly, it is a main object of this invention to provide a boiler construction which is readily adaptable to conversion from an up-draft type of boiler to a down-draft type of boiler or, conversely, from a down-draft to an up-draft, and in which the operating efficiency of the boiler when burning any type of fuel is comparable to the operating efficiency of a non-convertible boiler when burning the particular fuel for which it was designed.

A further object of the invention is to provide a steam and hot water boiler having upright or vertically extending sections in which certain of the said sections are invertable for the conversion of the boiler from a down-draft type of boiler to an up-draft type of boiler, or vice versa. A still further object is to incorporate in a single boiler the most efficient design for hand or automatic solid fuel firing and also the most efficient design for gas or liquid fuel firing, thereby substantially reducing the amount of manufacturing equipment and the number of operations ordinarily required for the production of boilers which will efficiently burn all kinds of fuel.

In carrying these and other objects, advantages and capabilities into effect reference should be had to the accompanying drawings which dis-

close a preferred embodiment of the invention as described in the specification.

Fig. 1 is a front elevation of the boiler with the first boiler section together with the doors and grate operating mechanism removed. The boiler is shown assembled for operation with coal or other solid fuel.

Fig. 2 is a vertical side sectional view of the boiler shown in Fig. 1.

Fig. 3 is a slightly magnified vertical side sectional view of the boiler taken on the line 3—3 of Fig. 4. The boiler is shown assembled with the intermediate sections inverted for operation with gas or liquid fuel, in which it will be noted that this figure shows a smoke hood different from the smoke pipe shown in Fig. 1.

Fig. 4 is a front vertical sectional view of the boiler assembled for operation with gas or liquid fuel, and as described in connection with Fig. 3.

Fig. 5 is a front elevation of one of the invertable intermediate sections of the boiler forming the subject matter of my invention.

Like numerals refer to like parts throughout the various views of the drawings.

It should be understood that the number of vertical boiler sections which may be used in forming a single boiler is subject to variation inasmuch as the number of intermediate sections may be optionally altered to increase or decrease the capacity of the boiler. Therefore, the four sections herein shown serve only to illustrate the invention.

Referring in detail to Figs. 1 and 2, a typical coal fired boiler is shown which comprises a front section, generally designated 1, one or more intermediate sections 2, and a rear section 3. The usual grates, shaker mechanism, and ash pit are provided and a suitable fire box or combustion space 4 above the grates is provided as indicated. Each of the sections is provided with a pair of side vertical water legs 5 in communication with each other at their lower ends through connections 6 and at their upper ends through connecting passages 7. The water legs communicate adjacent their upper ends with an upwardly arched water channel 8 which has its central portion 9 interconnected with the upper water chamber 11, thereby providing the flue passageways 12 and 12a. It is to be clearly understood that the precise construction or arrangement of the water passageways and the flue passageways is not important in the utilization of the invention herein disclosed and that the shape of each may be varied considerably

without departing from the spirit and scope of this invention.

As in the usual solid fuel burning boiler, the main body of the products of combustion passes upwardly and rearwardly impinging upon the exposed walls of the water passageways defining the combustion chamber 4 where the heat of combustion is thus transferred through the walls to the water. The burned and cooled products of combustion pass from the boiler through the smoke pipe 13 which is interconnected with the combustion chamber and the flue passageways at the rear uppermost portion of the rear boiler section 3.

The rear side of the rear boiler section 3 is preferably provided with flue apertures near each end of the section. When the boiler is assembled for operation as an up-draft type of boiler, the lower flue aperture should be closed with a suitable cover such as, for example, the cover 10, which, if desired, may assume the form of a draft door, and when the boiler is assembled for operation as a down-draft boiler, as hereinafter described, each upper flue aperture should be closed with a suitable cover such as, for example, the cover 20, which, if desired, may take the form of an explosion relief door.

The water is brought into the boiler through the return flow inlet 14 located at the rear lower end of section 3. It then may pass from one boiler section to the next through the passageways 6. The amount of water drawn into each water leg and section passageway will depend upon the rate at which the water in each section is being heated and caused to rise from the respective legs to the upper portions of each boiler section. When the boiler is used for generating steam, the water level will ordinarily be maintained in proximity to the passageways 7. The steam rising from the water is conducted from the boiler through the outlet 15, although more than one outlet may be utilized, if desired. If the boiler is used in connection with a hot water heating system the water is conducted from the boiler through the outlet pipe or pipes 15 to the system.

Attention is now directed to Fig. 3 in which the same four boiler sections which were shown and described in connection with Figs. 1 and 2 have been assembled with the intermediate sections 2 inverted, thereby providing a down-draft type of boiler for the efficient combustion of gas or liquid fuels. The usual burner 16 and the firepot 17 are here provided in place of the grates and other appurtenances which were provided on the solid fuel burning boiler. As indicated by the arrows the combustion of the fuel takes place within the firepot and the hot gases tend to rise within the boiler.

At this point an important element of my contribution is stressed, and specifically attention is directed to the fact that when my boiler is used as an up-draft type the smoke pipe 13 is attached to the upper rear side of the boiler section 3. However, when my boiler is used as a down-draft type under such conditions the smoke hood 19, which preferably comprises a separate attachment, is secured to the rear side of the boiler section 3. However, as distinguished from the smoke pipe 13, the smoke hood 19 extends to the bottom of the section 3 where it connects with the boiler flue apertures 18. In view of the fact that the smoke hood 19 is not used on the boiler when the latter is assembled as illustrated in Figs. 1 and 2, it is not shown.

Referring now to Fig. 4, the solid line arrows indicate the paths taken by the hot gases after combustion is completed within the firepot. The gases rise in the central portion of the boiler.

5 Then as they come in contact with the exposed water passage surfaces the gases are cooled and descend adjacent the interior sides of the boiler down past the firepot to the flues 12 provided by the intermediate sections 2. Then, as more clearly shown in Fig. 3, the gases pass through the apertures 18 in section 3 to the smoke hood 19 and then upwardly and out of the boiler as indicated.

The water return and the outlet piping are identical to that described in connection with Figs. 1 and 2 and the general course of the water through the boiler is likewise from the lower portion of the boiler upwardly through the water legs of the sections to the upper portion of the boiler and then out through the pipe, or pipes, 15, as shown by the dotted arrow lines in Fig. 4.

Referring now to Fig. 5 wherein one of the intermediate sections 2 is shown, it will be noted that if the section is assembled in a boiler in the position shown the water channel provides a support for the firepot 17 and at the same time provides for the relatively cool return water to be brought in close proximity to the combustion chamber immediately upon entering the boiler. If the boiler is to be used for the burning of solid fuels, one or more of the sections 2 are assembled in the boiler in the inverted position to that shown in Fig. 5. In the inverted position the water channel 3 is immediately above the combustion chamber and provides additional exposed surface within the boiler for the absorption of heat from the products of combustion. In addition, the rectangular shape of the opposite end of the section makes possible a large and conveniently shaped ash pit.

In order to facilitate the assembly, disassembly and reassembly of the boiler each section is provided with transverse openings therein for the reception of the usual hollow push nipples 21 which interconnect the water passageways. The boiler is preferably maintained in assembled relation by the upper and lower tie rods 22 and 23, respectively. However, if desired, other means may of course be employed for maintaining the individual boiler sections in cooperative assembled relation.

It is to be understood that the invention is not limited to the specific embodiments thereof described herein above, but includes all such modifications, variations and equivalents as fall within the scope of the appended claims.

I claim:

1. A boiler for hand or automatic coal-firing or for oil or gas-firing comprising a plurality of vertically extending sections, a front boiler section, a rear boiler section and at least one intermediate boiler section therebetween, the said intermediate section being invertible and capable of assembly with the said front section and the said rear section in either inverted or upright position, the rear section having a plurality of horizontal flue outlets, one of the latter being adjacent to the upper portion thereof for attachment of a smoke-hood for coal-firing or as a relief door opening for oil or gas firing, the other flue outlet being adjacent the bottom portion of the said rear section for attachment of a smoke-hood for oil or gas-firing or for a draft-box for coal-firing.

2. In a boiler having a plurality of vertically extending sections, a front section, a rear section, one or more intermediate sections therebetween, the said intermediate sections being capable of inversion when assembled with said front section and said rear section to convert the said boiler from an up-draft type of boiler to a down-draft type, or vice versa, the said rear section being provided with a plurality of flue apertures whereby in predetermined assembly with said intermediate sections, the upper of said flue apertures serves as an outlet for the gases of combustion for a coal-fired boiler, the lower of said flue apertures of the rear section being closed when the boiler is converted to an up-draft type and the upper of said flue apertures of the rear section being closed when the boiler is assembled for operation as a down-draft boiler.

3. In a boiler selectively suitable for coal, or oil burning or the like and having a plurality of vertically extending sections, a front section, a rear section, and one or more ported intermediate sections, the said intermediate sections being capable of assembly with said front and rear sections to convert the said boiler from an up-draft type of boiler to a down-draft type, or vice versa, the said rear section having upper and lower flue apertures, the arrangement of the said intermediate sections providing that when the sections are inverted in their assembly with said

10 rear section a horizontal flue passage is formed at the lower portion of the boiler to make the latter a down-draft type, the lower of said flue apertures of the rear section being closed when the boiler is converted to an up-draft type and the upper of said flue apertures of the rear section being closed when the boiler is assembled for operation as a down-draft boiler.

4. In an up-draft boiler having a plurality of vertically extending sections, a front section, a back section having upper and lower flue apertures, and one or more intermediate sections having a plurality of horizontally extending ports, intermediate sections being capable of converting the said boiler from an up-draft type to a down-draft type of boiler upon inverting said sections to transpose said ports from the upper to the lower portions of the said sections, whereby when the boiler is used for oil firing, the lower flue aperture of the back section serves as an outlet for the gases of combustion, the upper flue aperture of the said back section serving as relief means for the prevention of explosion of the combustible gases within the combustion chamber, the lower of said flue apertures of the rear section being closed when the boiler is converted to an up-draft type and the upper of said flue apertures of the rear section being closed when the boiler is assembled for operation as a down-draft boiler.

PAUL W. VANDENBERG.
